UNITED STATES PATENT OFFICE.

ALFRED G. BERG AND JOHN H. ROOT, OF NEWBURGH, NEW YORK.

CENTER-INDICATOR.

1,093,027.

Specification of Letters Patent. Patented Apr. 14, 1914.

Application filed May 27, 1911. Serial No. 629,872.

To all whom it may concern:

Be it known that we, ALFRED G. BERG and JOHN H. ROOT, both citizens of the United States, residing at Newburgh, in the county 5 of Orange and State of New York, have invented certain new and useful Improvements in Center-Indicators, of which the following is a full, clear, and exact specification, such as will enable others skilled 10 in the art to which it appertains to make and use the same.

This invention relates to a center indicating device and one of its objects is the provision of means whereby the same may be 15 quickly and conveniently placed in position, and when in place, the parts readily adjusted with relation to the work.

Another object is to provide such a device which may be attached to the cross 20 rails of boring mills.

Another object is to provide means on such a device whereby the same may be adapted for use on boring mills of different sizes and of different widths and depths of 25 cross rails.

Another object is to provide means on such device for quickly finding the central point on the cross rail in attaching the device thereto.

80 A still further object is to provide means whereby the scribe holding-bar forming a part of the device may be adjusted vertically and be thereby adapted to different sizes of work.

85 In the drawings,—Figure 1 is a front elevation, swing a portion of a boring mill and the indicating device in position thereon; Fig. 2 is a horizontal section on line 2—2 of Fig. 1; Fig. 3 is a vertical section 40 through the center of the device, showing certain parts in elevation; Fig. 4 is a front elevation; Fig. 5 is a section partly in elevation on line 5—5 of Fig. 3; and Fig. 6 is a detail section of the scribe holding- 45 arm.

Referring to the construction illustrated, A indicates a portion of a boring mill having the cross rail B, the rotary work-holding table C, and provided with tool holding 50ers D, D', and other operating parts which it will be unnecessary to describe since they may be of any of the well known forms and themselves form no part of our invention. Upon the table C is mounted the work E, 55 which is secured in position by the usual clamping devices indicated at E, E'.

Our device comprises upper and lower clamping members F, G, the upper one of which comprises a back plate H, having a plurality of vertical semi-circular bores indicated at H', and a front plate H² having similar vertical semi-circular bores indicated at H³, said bores acting as recesses to receive a plurality of adjustable guide standards I, I'. The back plate H and the front plate H² are adjustably held in clamping position against the guide standards I, I' by means of a bolt J passing through the front and back plates between said standards, said bolt being threaded at its outer end as at J', for the reception of a threaded hand wheel K, which, engaging the threads of the bolt J' is adapted to press the front and back plates H, H² toward each other to adjustably hold the standards I, I', 75 which latter are provided with stops L, L' for limiting their downward movement.

Both the upper and lower clamping members are provided with similarly-formed flanges to grip the cross-rail of the boring mill, and a description of one will sufficiently describe the other, similar letters of reference being used for each.

The back plate H of the upper clamping member is formed with a rearwardly extending flange M, having a recess M', through which passes a threaded bolt M², which bolt is longitudinally movable within the recess M' having a head M³ to limit its rearward movement. Mounted upon the threaded bolt M² is a threaded flange member M⁴, contacting with the front face of which is a washer M⁵, against which rests one end of a coiled spring M⁶ which lies partly within the recess M' and is adapted to be compressed against a shoulder M⁷ forming a part of said recess, its function being to keep the flange parts in distended position for ready attachment to the cross rail. The back plate H is also provided with a recess N, through which passes a small bolt N', having a head N² adapted to move within the enlarged rear end of said recess. The bolt N' is also provided with a holding nut N⁴ to limit the inward movement of the same. The bolt N' and also a similar bolt N⁵,—which latter being the same as that just described, requires no further description,—we will term position finders, since they are intended to abut within recesses on the cross-rail of the boring mill as shown at N⁶ in Fig. 3.

The lower clamping member G is formed with a forwardly extending horizontally recessed holder arm O, and rigidly mounted in said holder arm, on either side of said recess 5 are the lower ends of the two adjustable guide standards I, I'. Mounted within the horizontal recess of the holder arm O is a slide rod P, having a key-way P', engaging which is a set-screw P² projecting through 10 the upper side of the holder arm O, the arrangement being such that the slide rod P is capable of forward and backward movement, but not rotary movement, and may be secured in any desired position by means of 15 the set-screw P². The slide rod P is provided at its outer end with a holding member Q, vertically recessed at Q' to receive a vertically movable slide rod Q², said holding member having also a horizontal recess Q³, 20 the bore being threaded to receive a threaded bolt Q⁴, having a hand knob Q⁵, whereby the bolt Q⁴ may be set against the slide rod Q² to hold the same in any desired vertical position. The slide rod Q² is provided at its 25 upper end with a stop Q⁶ to limit its downward movement, and, at its lower end, with a collar Q⁷ to hold in place a sleeve Q⁸, provided with a laterally extending shank portion Q⁹ supporting a sleeve Q¹⁰ which supports a bearing bolt Q¹¹, comprising an enlarged bearing surface Q¹², a head Q¹³, and a threaded outer end Q¹⁴ adapted to receive 30 a hand wheel Q¹⁵. The bearing surface Q¹² is also provided with a sleeve Q¹⁶, passing 35 through a recess in which, and through a recess in the bearing surface Q¹² is a scriber-gage Q¹⁷, which is adapted to be held in any desired radial position on the sleeve Q¹⁰ by means of the hand wheel Q¹⁵, which latter 40 may be loosened or tightened to adjust said gage to different positions. By means of the sleeve Q⁸ said scriber-gage may be rotated to any position about the rod Q². It will be seen that by loosening the hand 45 wheel Q¹⁵, said gage may be rotated axially, may be rotated endwise about its own axis and may be rotated concentrically about the axis of the slide rod Q², thus constituting it, in effect, a universal gage. It may be adjusted vertically to suit different sizes of 50 work, by means of the slide rod Q² and the hand wheel Q⁵ and may be adjusted laterally by means of the slide rod P.

The upper and lower clamping members 55 F, G, by means of the spring adjustments provided in the flange members M and bolts M² adapt the machine to various depths of boring mill cross-rails and by means of the standards I, I' may be adjusted to cross-rails 60 of various dimensions in width, by which we mean the distance between the upper and lower surfaces of the cross rail.

We wish it to be understood that we do 65 not confine ourselves to the precise details of construction and arrangement herein set

forth, as modification and variation may be made without departing from the spirit of the invention as defined by the appended claims.

What we claim is:

1. The combination with a universally adjustable scriber-gage, of a plurality of clamping members for attachment to the cross rail of a boring mill, and a plurality of position-finders on said clamping members adapted to engage centering recesses on the cross rail. 70

2. The combination with a universally adjustable scriber-gage, of a plurality of clamping members for attachment to the cross rail of a boring mill, and a plurality of position-finders on said clamping members adapted to engage centering recesses on the cross rail, said position-finders comprising a plurality of retractable bolts. 75

3. The combination with a universally adjustable scriber-gage, of a plurality of clamping members for attachment to the cross rail of a boring mill, and a plurality of position-finders on said clamping members adapted to engage centering recesses on the cross rail, said position-finders comprising a plurality of spring-pressed bolts. 80

4. In an apparatus of the class described, the combination of a plurality of guide standards, a plurality of clamping members on said standards, with means for vertical adjustment, a slide rod carried by one of said clamping members arranged parallel with said standards, and vertically adjustable; and a scriber capable of universal adjustment with relation to said rod. 85

5. The combination of a plurality of guide standards, a plurality of clamping members on said standards, with means for vertical adjustment, said clamping members including a plurality of clamping flanges adjustable laterally with relation to said standards, said arrangement adapting the device for attachment to boring mill cross rails of different sizes, a holding-arm projecting laterally from one of said clamping members, a slide rod on said holding arm, and a scriber carried by said rod capable of universal adjustment with relation thereto. 90

6. The combination of a plurality of guide standards, a plurality of clamping members on said standards, one of said members being adjustable on said standards, said clamping members including a plurality of clamping flanges adjustable laterally with relation to said standards, said arrangement adapting the device for attachment to boring mill cross rails of different sizes, a holding-arm projecting laterally from one of said clamping members and adjustable longitudinally thereon, a slide rod adjustably mounted on said holding-arm, and a scriber supported by said rod capable 95

of universal adjustment with relation thereto.

7. The combination of a plurality of guide standards, a plurality of clamping members on said standards having means for vertical adjustment, said clamping members including a plurality of spring pressed clamping flanges adjustable laterally with relation to said standards, said arrangement adapting the device for attachment to boring mill cross rails of different sizes, a holding-arm projecting laterally from one of said clamping members and adjustable longitudinally thereon, a slide rod adjustably mounted on said holding-arm, and a scribe gage and a carrier therefor rotatably mounted on said rod.

8. The combination of a plurality of guide standards, a plurality of clamping members on said standards, adapted to grip the cross-rail of a boring mill, said clamping members including a plurality of adjustable clamping flanges, a holding-arm projecting laterally from one of said clamping members and adjustable longitudinally thereon, a slide rod vertically adjustable on said holding-arm, a scribe, a scribe carrier

mounted on said rod, arranged for rotary movement thereabout, and means on said carrier whereby said scribe may be rotated 30 concentrically with the axis of said carrier, and also rotated about and moved lengthwise of its own axis.

9. In a device of the class described, the combination of a plurality of clamping members, a holding-arm projecting laterally from one of said clamping members, a slide rod carried by and adjustably movable at right angles to said arm, a rotatable sleeve on said slide rod, a sleeve connected to the 40 last named sleeve, at right angles thereto, a recessed bearing bolt within the last named sleeve, a sleeve on said bolt having a recess registering with the recess in said bolt, a scribe arm within said recesses, and means 45 for tightening and loosening said parts to take a plurality of positions about the slide rod.
